UNITED STATES PATENT OFFICE.

ALLEN E. SNYDER, OF BOWMANSTOWN, AND MOSES SNYDER, OF LEHIGHTON,
PENNSYLVANIA.

TRAIN-CONTROLLING MECHANISM.

Application filed September 15, 1922. Serial No. 538,395.

To all whom it may concern:

Be it known that we, ALLEN E. SNYDER and MOSES SNYDER, citizens of the United States, residing, respectively, at Bowmanstown and Lehighton, both in the county of Carbon and State of Pennsylvania, have invented a new and useful Train-Controlling Mechanism, of which the following is a specification.

- 10 This invention relates to means for automatically arresting the further travel of a moving body traversing a railroad when a danger condition is imminent, and it has more particular reference to mechanism of
15 the governor operated type; that is to say—more specifically—mechanism including a ball governor which is automatically accelerated or retarded in direct ratio according to the speed of a locomotive or train, said
20 mechanism cooperating with a track device adapted for automatic elevation into the path of a trip member actuated by the ball governor to effect a partial or complete bleeding of a locomotive or train air line and thereby partially or entirely applying
25 the air brakes.

The primary object of our present invention is to provide novel means whereby the bleeding of the air line to effect a partial or
30 full application of the air brakes on a locomotive or train is automatically effected whether or not the danger condition imminent be a normal service or emergency one.

Another object of our invention is a novel
35 means for automatically locking the air line bleeding part or parts of a train controlling mechanism as hereinbefore referred to in the "open" position when the imminent danger condition is of an emergency nature.

40 A further object attained by our invention and resultant from the automatic application of the brakes on a locomotive or train whenever an emergency condition arises is the fact that the driver or other person in
45 charge of or operating said locomotive or train is forced to make personal investigation as to the cause of said emergency condition in order to effect the release of the locking means that retain the air line bleed or
50 bleeds in "open" position. More specifically defined a driver or any other person operating a locomotive or train equipped with our invention who may become temporarily or totally incapacitated through some unfore-

seen cause or due to negligence cannot approach and pass a danger signal or the like without said locomotive or train being automatically brought to a stop before the danger signal or the like is passed.

55 A still further object of this invention is to provide a novel train controlling mechanism of the type referred to which is simple in construction, easy to manufacture and install, not liable to get out of order, while it can be quickly applied to either steam, 60 electric or otherwise operated locomotives and trains with the expenditure of but little time and labor.

With the foregoing and other objects in view, as will become more apparent from 70 the following description, our invention consists essentially in certain novel features of construction, combinations and arrangements of parts hereinafter fully described and more specifically defined by the sub- 75 joined claims.

In the further disclosure of the invention reference will be made to the accompanying sheets of explanatory drawings constituting 80 a part of this specification, and in which like characters of reference designate the same or corresponding parts in all the views.

Figure 1 is an elevation of our improved train controlling mechanism as applied to one of the bogie axles of a locomotive, parts 85 being broken away and in section for a clearer disclosure of certain underlying mechanical movements.

Figure 2 is an enlarged fragmentary sectional end elevation of the governor drive 90 hereinafter more fully described.

Figure 3 is a side elevation looking towards the right hand of the preceding figure with parts broken away or in section to better disclose the underlying structures. 95

Figure 4 is a sectional plan taken substantially on the line 4—4 in Figure 5.

Figure 5 is an enlarged detail elevation—partly in section—illustrative of the connection between the governor controlled mechanically operated mechanism and the electrically actuated track device hereinafter more particularly described.

Figure 6 is a fragmentary detail face view of the mechanically operated trip device for 105 opening the air line bleed valves to effect the application of the brakes automatically.

Figure 7 is a similar view to the preced-

ing figure with the right hand portion broken away and illustrating the trip mechanism in the neutral position.

Figure 8 is a similar view to Figure 7 but showing the trip device in the position it occupies when our train controlling mechanism is operating to partially apply the air brakes or when the locomotive or train is approaching a distance or danger signal under proper control or at a predetermined safe running speed.

Figure 9 is a like view to the preceding figure but showing the position occupied by the trip device when an emergency condition arises, or when the brakes are automatically and fully applied to effect an immediate stoppage of a locomotive or train.

Figure 10 is a like view to Figure 9 with the trip member full line position indicating its passage over the first track device at a safe running speed, while the dotted line position shows said trip member locked, or as it remains after passing the second track device, and as it remains until manually released.

Figure 11 is a top plan view of the electrically actuated track device for effecting the oscillation of the trip member, with the cover therefor indicated by dotted lines.

Figure 12 is a rear face view of the trip member carrying plate and showing the latching means hereinafter more fully described; and,

Figure 13 is a vertical section through the trip member carrying plate and associated parts.

Referring more particularly to the drawings and specifically to Figure 1 thereof, the numeral 1 designates a railroad bed on which is disposed the cross-tie 2 conveniently—though not essentially—of channel cross section, said cross-tie serving as a support for the rail 3 that is held in place by removable splice plates 4; and said rail 3 is insulated from the tie 2 by insulation 5 of appropriate character. A fragmentary or broken portion of a pony truck bogie wheel is characterized by the numeral 6, while the axle therefor is designated as 7, said axle being mounted in the journal or grease-box 8 in any of the well known ways, and all of said foregoing elements forming no part of our present invention but being briefly referred to for a clearer understanding thereof.

According to our present invention, we drill the outer end of the aforesaid axle 7 to receive the screw threaded shank or axial projection 9 of a cylindric cup-like member 10, the same being securely locked against rotary or other displacement relative to the axle 7 by means of key or dowel screw 11 inserted through the closed-in inner end 12 of said cup-like member 10. This cup-like member 10 serves as a housing for an appro-

priate universal 13 at one end of a connecting rod 14, and disconnection of said universal 13 from the cup-like member 10 being effectively prevented by a retaining collar 15 and set screw 16 as will be clearly understood by those acquainted with the art to which our invention appertains.

Supported from one or both side walls of the grease-box or journal 8 by means of an angle, bracket or brackets 17 held in place by set screws 18 is a tubular or like casing or housing 19 provided with vertically disposed flanges 20 connectable to the aforesaid angle bracket or brackets 17 by means of bolts or set screws 21. Additional rigidity and support for the tubular or like casing 19 may be ensured by clamping to the underside of the grease-box or journal 8 a laterally disposed brace plate or the like 22 provided with one or more tubular distance pieces 23 through which is or are passed a bolt or bolts 24 the head or heads 25 whereof engages or engage the inner lower wall of said tubular or like casing 19, while clamping bolts 26 and a bridge piece 27 effect the connection of the brace plate 22 to the grease box or journal 8.

Integral with or secured within the outer end of the aforesaid tubular casing 19 is a vertical bearing 28 in which is rotatably journaled a shaft 29 that seats on an anti-friction thrust bearing 30 adjustable by means of a screw threaded support 31 and lock screw 32. The vertical shaft 29 has feathered thereon a vertically slidable sleeve 33 provided at its lower part with a grooved enlargement 34. Pivotedly mounted between lugs 35 provided for the purpose at the upper end of the shaft 29 are a pair of governor balls 36 which in turn are connected by short links 37 to the aforesaid vertically slidable sleeve 33. The grooved enlargement 34 is fitted with an antifriction collar 38 having lateral pintles 38' engaging in the forked ends of the stirrup portion 39 of the lever 40 fulcrumed at 41 in the upper part of a standard 42 integral with a laterally projecting bar or member 43 on the vertical bearing 28. A contractile spring 44 is connected at one end 45 to the lever 40 and at the other end 46 to the laterally projecting bar or member 43, and it will be readily understood that this spring 44 normally tends to pull the vertically slidable sleeve 33 downwards in opposition to the momentum of the governor balls 36.

Referring back again to the laterally projecting bar or member 33, it will be seen that it is provided with an upstanding vertical portion 47 in parallel spaced relation relative to the standard 42, and furthermore it is to be noted that the outer or free end of the aforesaid fulcrumed lever 40 projects through a vertical slot 48—Figures 4, 12 and 13—in said vertical portion 47 and engages

in an aperture or hole 49 near the upper edge of a vertically movable slide 50. This slide 50 is guided in appropriate gib 51 secured to or formed on the outer face of the vertical portion 47, and it is limited in its downward movement by a transverse rib or stop 52 as well as being provided with a rearwardly projecting pin 53 extending through the slot 48 for a purpose later on explained.

10 Pivoted pendulum fashion on an appropriate stud or pivot pin 54 securely mounted intermediate the upper and lower ends of the slide 50 is a depending arm or trip member 55 which is adapted for oscillation 15 in either direction as later on explained. It is also to be particularly observed that this depending arm or trip member 55 will be raised and lowered by the aforesaid fulcrumed lever 40 under the action of—and in 20 accord with—the momentum of the governor balls 36 through the connections just described. The upper part or head of the depending arm or trip member 55 is fashioned or provided at each side with opposed stepped or notched out upper and lower parts 56, 57 respectively that are adapted to co-operate with head members 58 secured to the stems of bleed valves 59—Figure 4—fitted in the air line 60. Referring more specifically to Figures 4 to 10 25 in the following description, reference will be directed in the singular to only one of the bleed valves 59 and associated parts, it being obvious that the opposed valve and 30 associated parts will be duplicates thereof but reversely disposed.

Each bleed valve 59 in the air line 60 is, as will be obvious, under the action of a compression spring 61, and that when 40 opened in the direction indicated by the arrows in Figure 4 it will be held so opened by the engagement of either the lower or upper notched out part 57, 56 respectively on the head portion of the depending arm 45 or trip member 55 as later on more fully explained, whereupon the air in the air line 60 will escape through the valve cage 62 and continue to do so until the particular valve 59 so opened is again closed, and 50 thereby apply the air brakes. In order to provide an automatic means for returning the depending arm or trip member 55 to a normally vertical pendent position when the head portion is released from engagement with either of the head members 58 55 we employ a pair of opposed flat recoil or leaf springs 63, 63 which are conveniently secured at their upper parts in the slotted outer projecting end of the hereinbefore described pivot pin or stud 54 by means of 60 a split pin or rivet 64. The lower or free ends of these recoil or leaf springs 63 are slightly flared or outwardly curved to straddle a laterally projecting pin or stud 65 secured centrally of and in a convenient

position in the depending arm or trip member 55; and, as will be perfectly clear to those acquainted with the art, said recoil or leaf springs 63 will operate to automatically return the depending arm or trip 70 member 55 to its neutral or vertical position whenever either of the head members 58 is released from engagement with the aforesaid notched out parts 56 or 57.

Integral with each of the aforesaid head members 58 is a lateral arm 66 the free or angled end 67 whereof is slidably mounted in a horizontal slot 68 provided for the purpose in the upstanding vertical portion or wall 47 aforesaid. On an examination of 80 the drawings it will be clearly seen that the aforesaid free or angled end 67 of the lateral arm 66 lies in the path of a pair of opposed upper and lower latch levers 69, 70 respectively, pivoted on studs 71 and 85 under the action of compression springs 72 that normally tend to force said latch levers 69, 70 towards each other, as will be easily understood by those conversant with such mechanisms. These latch levers 69, 70 are respectively formed with a tooth or projection 73, 74 in slightly spaced relation relative to each other; that is to say with respect to the showing illustrated, the tooth 73 on the upper latch lever 69 is disposed 90 in advance of the tooth 74 on the lower latch lever 70; or, said teeth may be arranged vice versa. In other words, the tooth 73 is positioned to have co-operative latching engagement with the free or angled end 67 of the laterally movable arm 66 in advance of the tooth 74 for a purpose later on more explicitly set forth. Thus it will be easily seen that when the tooth 73 engages the free or angled end 67 the particular bleed valve 59 associated therewith will be held open to a predetermined extent, while when said angled end 67 is engaged by the tooth 74, said valve 59 will be opened 100 to a greater extent and held open and so locked until manually released or re-closed, as later on explained. Suitably connected to each of the lower latch levers 70 is a depending pull rod or chain 75 having a finger ring or hand hold 76 at its lower end whereby the said latch levers 70 may be released from latching engagement with the associated angled ends 67. From the foregoing it will be readily seen that by the provision 110 of the opposed latch levers 69, 70 at each side of the device the bleed valves 59 can be held open in two different relative positions, and in this connection we wish to here point out that the first position provides for what may be termed a normal service application of the air brakes on the engine or train equipped with our invention, whereas the second position ensures an emergency application of said air brakes. 120 Referring once again to the governor 130

mechanism which controls and operates the hereinbefore described mechanism through the oscillation or rocking of the fulcrumed lever 40 and having reference more particularly to Figures 1 to 3 of the drawings it will be seen that the connecting rod 14 is provided at its outer end with an universal 77 having a sliding fit in the hub 78 of a bevel gear 79 rotatably mounted upon a 10 stub axle 80 integral with or securely connected to a boss 81 laterally projecting in normal axial alignment with the axis of the bogie wheel axle 7, a locking collar or other suitable antifriction device 82 ensuring the 15 frictionless running of said bevel gear 79 on the stub axle 80. This bevel gear 79 meshes into and is adapted to drive a second bevel gear 83 securely keyed or otherwise mounted on the vertical shaft 29, and it will 20 accordingly be clearly apparent that the momentum of the governor balls 36 will accord in direct ratio with the speed of the rotating axle 7. Further, it will be readily apparent that by the employment of the 25 slidable universal 77 provision is made for a constant and direct drive of the governor balls 36 no matter what displacement of the axial alignment of the bogie axle 7 relative to the axis of the stub axle 80 may be, such 30 as when taking curves in the railroad track, or consequent upon unevenness in the road bed. This feature we deem of prime importance as it is well known in the art that rolling stock axles are subject to constant 35 and rapid vibratory changes in all directions when travelling over ordinary road beds.

In conjunction with the mechanism hereinbefore described and in order to complete the automatic phase of our invention we arrange in predetermined positions at one or 40 both sides of the track and in juxtaposition to the rail 3, over which hangs the depending arm or trip member 55, a box-like casting or block 84 appropriately secured on a 45 rigid base 85—Figure 1. This box-like casting or block 84 is formed with an upper compartment 86 closed by a gravity fall cover or hood 87, suitably hinged at 88 to one 50 wall 89 thereof that is at right angles to the road bed. This cover or hood 87 as will be clearly seen from the lower part of Figure 5 is made of inverted scoop-shape in cross-section so that it serves to close in the aforesaid compartment 86 at all times, and there- 55 by protect the mechanism therein contained from the ravages of inclement weather and other influences or matter that might serve to injure or destroy the same. Journaled in antifriction bearings 90 within the compartment 86 is a transverse shaft 91 on which is a worm-wheel 92 adapted to be partially rotated or turned in either direction by a worm-drive 93 on the armature shaft 94 of an electric motor 95, connected by wires 96 60 with any suitable source of electromotive

energy. Secured on the transverse shaft 91 and centrally longitudinal of the compartment 86 relative to the track is a cam or eccentric 97 which serves to raise the hereinbefore described cover or hood 87 into the path 70 of the depending arm or trip member 55 as later on explained. In order that the movements of the transverse shaft 91 may synchronize with the operation of the ordinary and well known block signals or distance 75 and home boards,—not shown—we employ what may be conveniently termed a timer, or control switch 98 that is securely mounted on the transverse shaft 91. This timer or control switch 98—Figures 5 and 11—consists of an insulate material drum having bedded in its peripheral surface a metal contact strip 99 which is gated or interrupted—as shown—and for a purpose hereafter explained. Similarly bedded into one end of 80 the timer or control switch 98 is an annular contact washer 100 that is in electrical connection with one end 101 of the peripheral strip 99. Supported on a bearing bracket 102 adjacent the timer or control switch 98 is 85 an insulate block 103 that supports upper and lower spring contacts 104, 105 respectively, which cooperate with the peripheral strip 99, while a third spring or ground contact 106 engages the annular contact washer 90 100 101 106. Wires 107, 108 connect the contacts 104, 105 with a similar timer or control switch—not shown—operating simultaneously with the block signal or semaphore board, whereas a wire 109 connects the ground contact 106 to one terminal of a storage battery in circuit with the motor 95. Thus it will be readily understood by those 105 acquainted with the art that the timer or control switch 98 can be arranged so that as the block signal or semaphore board is moved from the “danger” to the “line clear” position the motor 95 can be energized to effect a partial left hand turn—for example—to the cam or eccentric 97 which will 110 permit the cover or hood 87 to descend by gravity downwards from out of the path of travel of the depending arm or trip member 55. On the other hand a reversal of the signal from the “line-clear” to the “danger” 115 position will effect a partial right-hand turn of the cam or eccentric 97 and the automatic elevation of the cover or hood 87. This part of our invention is only briefly referred to as it will be perfectly obvious that any appropriate track device adapted for automatic elevation into and out of the path of the depending arm or trip member in synchronism with the operation of the block signal or semaphore boards will be equally 120 effective, therefore we desire it clearly understood that the electrical mechanism just described is not to be identified per se as a part of our present invention, but that it has been shown and briefly described in 125 130

order for a clearer understanding of the functioning of our said invention.

An appropriate casing or cover 110 is suitably supported over the governor mechanism and associated parts and braced by a distance piece or pieces 111 to the aforesaid upstanding vertical portion 47 of the laterally projecting bracket member 43.

From the foregoing description it will be readily understood that as the locomotive or train travels along the railroad 3 that the bevel gear 79 will be rotated by the connecting rod 14 in strict conformity with the axle 7, and, through said gear 79 meshing with the bevel gear 83, drive the vertical shaft 29, the speed of rotation of said shaft 29 being in direct ratio or proportion to that of the travelling locomotive or train.

Now it will be perfectly obvious that as the momentum of the shaft 29 increases there will be a co-related expansion or lifting of the governor balls 36. This expansion of the governor balls 36 will elevate the vertically slidable sleeve 33 and through the stirrup portion 39 rock the lever 40 on its fulcrum or pivot 41 with a consequent lowering of said lever's outer or free end. As a result of the lowering of the aforesaid outer or free end of the lever 40 and its operative engagement in the aperture or hole 49 of the slide 50, the latter will be downwardly moved in the guides or gibs 51, and through the pivotal mounting thereon at 54 of the depending arm or trip member 55, said depending arm or trip member 55 will be lowered to the position indicated in Figure 5—for example. Now, in the event of the block signal or semaphore board being set at "danger" which carried with it the automatic raising of the cover or hood 87 of the block 84 as hereinbefore set forth, it will be perfectly obvious that, as the depending arm or trip member 55 is carried forward in the direction of the arrow in Figure 5 it will strike or impact with said cover or hood 87 and be swung—pendulum fashion—on its pivot pin 54 to the position shown by Figure 8 for example. Now, assuming, by way of a clearer understanding of our present invention that the position of the depending arm or trip member shown by Figure 8 is what we term the first block line or safety control position of our mechanism, or as hereinbefore referred to that position when the locomotive or train is automatically brought to or traveling at a safe running speed—that is to say more specifically under proper control—the rocking of the depending arm or trip member 55 in the manner just set forth will result in the outward projection of the head member 58 and its retention so held by the cooperation therewith of the upper notched out part 56. As will be readily seen this movement outwards of the head member 58 will result in a partial or predetermined opening of the associated bleed valve 59 in the air line 60, and the application of the air brakes, and said bleed valve 59 will be automatically retained open by the engagement of the tooth 73 on the upper latch lever 69 with the associated angled end 67 of lateral arm 66 on said head member 58. Still further it is to be particularly noted that in connection with the just described movement of the depending arm or trip member 55 the upper spring 72 serves to force the latching lever 69 downwards to effect engagement of the tooth 73 thereon as just set forth. The partial retardation of the locomotive or train speed due to the movement of the mechanism as above described will automatically bring about a reduction in the speed or momentum of the governor balls 36, and as will be clearly apparent to those acquainted with the art the lever 40 will be reversely rocked on its fulcrum 41, thereby effecting the elevation or raising of the slide 50, and bearing in mind that the mechanism has been operated under safe conditions the rearwardly projecting pin 53 on said slide 50 will contact with the underside of the free end of the latch lever 69 and raise same in opposition to the action of the spring 72, thus disengaging the tooth 73 from the angled end 67 and thus allowing the bleed valve 59 to automatically reclose. Incidentally we desire to here remark that the operation of our train controlling mechanism as just described is intended to conform with normal railway service conditions and as a safeguard against a locomotive or train being accidentally or inadvertently run at a predetermined set speed past any signal even though no danger is closely imminent, for example, a locomotive or train equipped with our controlling mechanism cannot pass a first block signal or distance semaphore board set at "danger" without being automatically retarded to a safe running speed or stopped before reaching the second block signal or home semaphore board. Still further it is to be noted that when the depending arm or trip member 55 is released by the contact of pin 53 with the free end of the upper latch lever 69, said depending arm or trip member 55 will be automatically returned to a pendent vertical position under the operative action of the expanded recoil or leaf spring 63 against the pin or stud 65 thereon. The first block signal or distance semaphore board position of our train controlling mechanism is also illustrated in Figure 1, that is to say more specifically the relative position of the depending arm or trip member 55 to the full line showing of the cover or hood 87 is intended to be in conformity with such conditions. And it will be obvious that by making the lever 55 movable up and down in

accordance with the speed of the train, the engineer can carry his train past a caution signal without operating the brakes automatically provided the speed of the train be sufficiently low.

Now, assuming that through some unforeseen or accidental cause the driver or other person in charge of a locomotive or train fitted with our controlling mechanism should be stricken or otherwise incapacitated either before or after passing the first block signal or distance semaphore board as just described and approach the second block signal or home semaphore board even at a safe running speed we have devised our mechanism so that said locomotive or train will be instantly stopped. To this end we arrange the second track device or block 84 at a sufficiently higher elevation so that when the cover or hood 87 thereof is automatically raised as hereinbefore described it will be at the elevation indicated by the dot-and-dash line position 112 shown on Figure 1. Now it will be perfectly obvious to those conversant with the art that as the depending arm or trip member 55 is passed over the cover or hood 87 in the manner set forth herein, said arm or trip member 55 will be moved further outwards relative to its normal vertical pendent position. In other words the depending arm or trip member 55 will be swung through a wider arc which will result in the head member 58 engaging in the lower notched out part 57. Instantly said movement takes place the lower latch lever 70 will be upwardly sprung under the action of the lower compression spring 72, whereupon the tooth 74 on said latch lever will be placed in locked engagement at the back of the associated angled end 67, whereupon the bleed valve 59 will be securely held open under emergency application of the air brakes and will arrest the further travel of the locomotive or train whereupon the governor balls 36 will descend and force the slidable sleeve 33 downwards thereby rocking the lever 40 in a reverse direction with the result that said lever's free end will lift the slide 50 and cause its return to neutral position, while the rearwardly projecting pin 53 thereon will not elevate the lower latch lever 70 consequent upon the fact that said lever 70 is comparatively much shorter than the upper latch lever 69 and therefore clear of said pins line of travel. An examination of the drawings will make this point perfectly clear, and it will be readily seen that in order to release the lower latch lever 70 from locking connection with the associated angled end 67 the driver or some other person on the locomotive or train must descend therefrom and exert a manual downward pull upon the finger ring or hand hold 76 which through the medium of the pull rod. 65 or chain will effect disengagement of the

tooth 74 from locked connection with the aforesaid angled end 67. Still further it is to be clearly understood that the second block signal or home semaphore board position assumable by our train controlling mechanism has been devised solely for taking care of unexpected or emergency conditions arising. On the other hand it will also be readily understood that where a set speed of travel for locomotive or train is exceeded our novel controlling mechanism may be adjusted so that the depending arm or trip member 55 may be arranged to clear the first block signal or distance board elevation of the cover or hood 87 as indicated by the full line showing of said arm or trip member 55 in Figure 10; whereas the second block signal or home board elevation of the cover or hood 87 will effect the tripping of the device as hereinbefore described, and as indicated by the dot-and-dash line position of the depending arm or trip member in said Figure 10. It will of course be clearly apparent that the showing in Figure 10 is solely to clarify the point at bar, namely, that a predetermined acceleration of the governor balls 36 may be settled on which would effect the elevation of the slide 50 to a definite point before the depending arm or trip member 55 would become operative to effect the opening of the bleed valve 59 to a position for application of the air brakes. From the foregoing it will be apparent that our novel train controlling mechanism is rendered automatic under all service or emergency conditions no matter to what extent or not the governor balls 36 are accelerated or retarded if the second block signal or semaphore board position of the cover or hood 87 is set at a predetermined elevation relative to the tip or lower end of the depending arm or trip member 55, while the air brakes will be automatically applied thereby and cannot be removed until the lower latch lever 70 is manually released. Obviously the bleed valves 59 will re-close under the action of the springs 61, while the track devices 84 may be actuated independently of the block signals or semaphore boards.

From the foregoing description and an examination of the drawings it will be readily understood that our present invention provides a train controlling mechanism which will operate automatically to stop a locomotive or train in case the engine-man or other person in charge thereof fails to observe or be governed by restrictive signal indications. Still further it will be clear that our invention provides an adequate automatic train-control which will be found fool-proof should the driver of a locomotive or train provided therewith fail to heed signal indications and control his locomotive or train accordingly.

Another advantage inhering to our present

invention is its easy application to and adaptability for direct operation by a moving axle of a locomotive or train, while its installation necessitates a minimum expenditure of time and labor. Obviously the mechanism hereinbefore described is equally applicable to steam, electric or otherwise propelled locomotives or trains, whereas it can be installed on one or both sides thereof to accommodate the invention to single track systems.

While we have shown and described the best form of our invention at present known to us, it will be obvious that the same is susceptible of considerable variation, as well as other embodiments of the several parts thereof, and the right is hereby reserved to make all such reasonable changes and modifications therein as fairly fall within the scope of the appended claims.

Having described our invention, what we claim as new and desire to secure by Letters Patent, is:—

1. In a train controlling mechanism the combination with a rotating axle thereof and the air brake line of ball governor mechanism driven by said axle, means adjacent the governor mechanism having a vertically movable pendulum trip member carried thereby, means connecting the governor mechanism with the trip member carrying means, means actuatable by the trip member for effecting an initial opening of the bleed in the air brake line to cause a normal application of the brakes, means actuatable by said trip member for further opening said bleed to effect an emergency application of the brakes, means for locking said bleed in the last mentioned open position, and manually operable means for releasing the locking means before the train can be re-started.

2. In a train controlling mechanism the combination with a rotating axle thereof and the air brake line of ball governor mechanism driven by said axle, means adjacent the governor mechanism having a vertically movable pendulum trip member carried thereby, means connecting the governor mechanism with the trip member carrying means, means actuatable by the trip member for effecting an initial opening of a bleed in the air brake line to cause a normal application of the brakes, means for automatically releasing the aforesaid bleed opening means under a predetermined service condition, means actuatable by said trip member for further opening said bleed to effect an emergency application of the brakes, means for locking said bleed in the last mentioned open position, and manually operable means for releasing the locking means before the train can be re-started.

3. A train controlling mechanism including a ball governor adapted for operation by a moving axle of the train, a vertically

movable pendulum trip member, means connecting the ball governor with the trip member whereby the centrifugal acceleration and retardation of said ball governor respectively effects a lowering and raising of the trip member, means actuatable by the trip member for effecting an initial opening of a bleed in the air brake line to cause a normal application of the brakes, means for automatically releasing the aforesaid bleed opening means under a predetermined service condition, means actuatable by said trip member for further opening said bleed to effect an emergency application of the brakes, means for locking said bleed in the last mentioned open position, and manually operable means for releasing the locking means before the train can be re-started.

4. A train controlling mechanism including a ball governor adapted to be driven through an universal connection by a moving axle of the train, said ball governor including a standard in which the governor shaft is journaled and a spaced upstanding member having a vertically movable slide, a pendulum trip member supported on the slide and adapted to be moved vertically by the ball governor, said trip member having opposed stepped notched-out parts in the head thereof, valved air line bleeds in spaced relation to the aforesaid trip member adapted to be opened by the notched-out parts when said trip member is swung on its pivot, means actuatable by the trip member for effecting an initial opening of either of the valved air line bleeds to cause a normal application of the brakes, means for automatically reclosing said valved air line bleeds under a predetermined service condition, means actuatable by said trip member for further opening the valved air line bleeds to effect an emergency application of the brakes, means for locking said valved air line bleeds in the last mentioned open position, manually operable means for releasing the locking means before the train can be re-started, and track devices adapted for automatic elevation into the path of the trip member to effect its movement when necessary and gravity recession when not so required.

5. In a train controlling mechanism the combination with a rotating axle and the air brake line of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member,

a spring influenced rock lever supported intermediate the governor and the pendulum trip arm and adapted to effect its lowering and raising simultaneously with the 5 rotation of the governor balls. said pendulum trip arm having opposed stepped notched out parts of different radius relative to its pivotal point, valved air line bleeds in spaced rotation to the trip arm adapted to 10 be relatively opened by the stepped notched out parts aforesaid when said trip arm is swung on its pivot in either direction, means for holding either of the valved air line bleeds at the primary open position and 15 means for allowing same to automatically re-close under a predetermined service condition, means for locking either of the valved air line bleeds in the secondary or emergency open position to effect an immediate stoppage of the train, and manually operable means for releasing the locking means before the train can be re-started.

6. In a train controlling mechanism the combination with a rotating axle and the air 25 brake line, of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, 30 a pendulum trip arm vertically movable on slide in the upstanding member, a spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, valved air line bleeds in spaced relation to the trip arm adapted to be relatively opened by the stepped notched out parts aforesaid when said trip arm is swung on its pivot in either direction, means for holding either of the valved air line bleeds at the primary open position and means for allowing same to automatically re-close under a predetermined service condition, means for locking either of the valved air line bleeds in the secondary or emergency open position to effect an immediate stoppage of the train, manually operable means for releasing the locking means before the train can be re-started, and means for automatically returning the trip arm to a vertical pendent position when freed from operative connection with valved air line opening means.

7. In a train controlling mechanism the combination with a rotating axle and the air 40 brake line of a centrifugal governor adapted to be driven by an universal connection 45

coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member, a spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, spring influenced spaced valves in the air line having head members for engagement by the stepped notched out parts of the trip arm when swung in either direction and outwardly directed angled lateral portions the free ends whereof project through elongated slots in the aforesaid upstanding member, opposed spring influenced and pivotally mounted latch levers the inner ends whereof overlap and lie in the path of the aforesaid rock lever for holding either of the valved air line bleeds in a primary open position, means for automatically re-closing the valved air line bleeds under a predetermined service condition, means for locking either of the valved air line bleeds in a secondary or emergency open position to effect an immediate stoppage of the train, manually operable means for releasing the locking means before the train can be re-started, and means for automatically returning the trip arm to a vertical pendent position when free from operative engagement with either of the valved air line head members.

8. In a train controlling mechanism the combination with a rotating axle and the air 50 brake line of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member, a spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, spring influenced spaced valves in the air line having head members for engagement by the stepped notched out parts of the trip 55 60 65 70 75 80 85 90 95 100 105 110 115 120 125 130

- arm when swung in either direction and outwardly directed angled lateral portions the free ends whereof project through elongated slots in the aforesaid upstanding member, 5 opposed spring influenced and pivotally mounted latch levers the inner ends whereof overlap and lie in the path of the aforesaid rock lever for holding either of the valved air line bleeds in a primary open position, 10 a laterally projecting pin on the pendulum trip arm carrying and vertically movable slide for cooperation with the overlapping inner ends of the latch levers to effect an automatic re-closing of the valved air line 15 bleeds under a predetermined service condition, means for locking either of the valved air line bleeds in a secondary or emergency open position to effect an immediate stoppage of the train, manually operable means for releasing the locking means before the train 20 can be re-started, and means for automatically returning the trip arm to a vertically pendent position when freed from operative engagement with either of the valved air 25 line head members.
9. In a train controlling mechanism the combination with a rotating axle and the air brake line of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member, a 30 spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, spring influenced spaced valves in the air line having head members for engagement by the stepped notched out parts of the trip arm when swung in either direction and outwardly directed angled lateral portions the free ends whereof project through elongated slots in the aforesaid upstanding member, 35 opposed spring influenced and pivotally mounted latch levers the inner ends whereof overlap and lie in the path of the aforesaid rock lever for holding either of the valved air line bleeds in a primary open position, a laterally projecting pin on the pendulum trip arm carrying and vertically movable slide for cooperation with the overlapping inner ends of the latch levers to effect an automatic re-closing of the valved air line bleeds under a predetermined service 40 condition, 45 reversely operating opposed spring influenced and pivotally mounted latch levers for locking either of the valved air line bleeds in a secondary or emergency open position to effect an immediate stoppage of the train, a manual pull member on each of the last mentioned latch levers for effecting its release from locked position before the train can be re-started, and means for automatically returning the trip arm to 50 a vertically pendent position when freed from operative engagement with either of the valved air line head members.

10. In a train controlling mechanism the combination with a rotating axle and the air brake line of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member, a spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, spring influenced spaced valves in the air line having head members for engagement by the stepped notched out parts of the trip arm when swung in either direction and outwardly directed angled lateral portions the free ends whereof project through elongated slots in the aforesaid upstanding member, 70 opposed spring influenced and pivotally mounted latch levers the inner ends whereof overlap and lie in the path of the aforesaid rock lever for holding either of the valved air line bleeds in a primary open position, a laterally projecting pin on the pendulum trip arm carrying and vertically movable slide for cooperation with the overlapping inner ends of the latch levers to effect an automatic re-closing of the valved air line bleeds under a predetermined service condition, 75 reversely operating opposed spring influenced and pivotally mounted latch levers for locking either of the valved air line bleeds in a secondary or emergency open position to effect an immediate stoppage of the train, manually operable means for releasing the last mentioned latch levers before the train can be re-started, and means for automatically returning the trip arm to a vertically pendent position when freed from operative engagement with either of the valved air line head members.

11. In a train controlling mechanism the combination with a rotating axle and the

air brake line of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member, a spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, spring influenced spaced valves in the air line having head members for engagement by the stepped notched out parts of the trip arm when swung in either direction and outwardly directed angled lateral portions the free ends whereof project through elongated slots in the aforesaid upstanding member, opposed spring influenced and pivotally mounted latch levers the inner ends whereof overlap and lie in the path of the aforesaid rock lever for holding either of the valved air line bleeds in a primary open position, a laterally projecting pin on the pendulum trip arm carrying and vertically movable slide for cooperation with the overlapping inner ends of the latch levers to effect an automatic re-closing of the valved air line bleeds under a predetermined service condition, reversely operating opposed spring influenced and pivotally mounted latch levers for locking either of the valved air line bleeds in a secondary or emergency open position to effect an immediate stoppage of the train, a manual pull member on each of the last mentioned latch levers for effecting its release from locked position before the train can be restarted, and spring recoil means for automatically returning the trip arm to a vertically pendent position when freed from operative engagement with either of the valved air line head members.

12. In a train controlling mechanism the combination with a rotating axle and the air brake line of a centrifugal governor adapted to be driven by an universal connection coupled to said rotating axle, said centrifugal governor including a bearing and an integral spaced upstanding member for attachment to an axle box, a vertically disposed shaft rotatable in the aforesaid bearing having governor balls at the upper end thereof, a gear drive for the vertical shaft operable by the aforesaid universal connection, a pendulum trip arm vertically movable on slide in the upstanding member, a spring influenced rock lever supported intermediate the governor and the pendulum trip arm and adapted to effect its lowering and raising simultaneously with the rotation of the governor balls, said pendulum trip arm having opposed stepped notched out parts of different radius relative to its pivotal point, spring influenced spaced valves in the air line having head members for engagement by the stepped notched out parts of the trip arm when swung in either direction and outwardly directed angled lateral portions the free ends whereof project through elongated slots in the aforesaid upstanding member, opposed spring influenced and pivotally mounted latch levers the inner ends whereof overlap and lie in the path of the aforesaid rock lever for holding either of the valved air line bleeds in a primary open position, a laterally projecting pin on the pendulum trip arm carrying and vertically movable slide for cooperation with the overlapping inner ends of the latch levers to effect an automatic re-closing of the valved air line bleeds under a predetermined service condition, reversely operating opposed spring influenced and pivotally mounted latch levers for locking either of the valved air line bleeds in a secondary or emergency open position to effect an immediate stoppage of the train, a manual pull member on each of the last mentioned latch levers for effecting its release from locked position before the train can be restarted, and spring recoil means for automatically returning the trip arm to a vertically pendent position when freed from operative engagement with either of the valved air line head members.

In testimony whereof we have affixed our signatures at Bowmanstown, county of Carbon and State of Pennsylvania, this 12th day of September, 1922.
